UNITED STATES PATENT OFFICE.

LOUIS DE MARKUS, OF MONTROSE, PENNSYLVANIA.

METHOD AND APPARATUS FOR PULVERIZING.

Application filed March 16, 1923. Serial No. 625,506.

To all whom it may concern:

Be it known that I, LOUIS DE MARKUS, a citizen of the United States, residing at Montrose, county of Allegheny, State of Pennsylvania, have invented a new and useful Improvement in Methods and Apparatus for Pulverizing, of which the following is a full, clear, and exact description.

This invention relates to methods and apparatus for pulverizing and is particularly adapted for pulverizing coal in connection with powdered coal combustion systems.

My invention provides an apparatus of improved construction which may be used in connection with, and adjacent to, a combustion apparatus, or may be separated therefrom as desired. Heretofore, a great objection to pulverizing apparatus has been that the particles at different stages of grinding or reduction are not graded or separated according to their fineness. In order to reduce relatively large lumps it is necessary to use a coarse grinding mill. It is desirable, however, that such a mill should be rapidly cleared of small particles since their presence clogs the action of the mill and materially reduces its efficiency.

My invention provides for passing a conveying fluid through the pulverizing apparatus and for varying the velocity of such fluid to effect a gradation of particles of the material being pulverized. As is well known, a moving fluid, as, for example, air, will carry particles up to a certain mass dependent principally on the air velocity. By varying the velocity of the conveying fluid, I effect a suitable gradation of the particles in a very efficient manner.

The invention also includes a free fluid path through the entire pulverizing apparatus. This insures a free passage for particles which have already been sufficiently reduced at any point in the apparatus and they may be carried away without being subjected to a further reducing action. In the reduction of coal or similar materials, the breaking up of a large particle generally results in the production of smaller particles of varying size. Many of these are as small as desired and my invention permits of immediately carrying these sufficiently reduced particles out of the apparatus, thereby avoid-

ing clogging and materially increasing the capacity of the apparatus.

To reduce coal to the required fineness, it is generally necessary to remove the moisture. In the present invention, the conveying fluid acts as a drier and, being in intimate contact with the coal at all stages of reduction, will generally dry the coal without employing any of the usual driers. For very wet coal I provide for preheating the air to facilitate the drying action. The elimination of a separate drying operation effects a great saving over apparatus as heretofore constructed.

In the accompanying drawings, which are largely diagrammatic and which illustrate the present preferred embodiment of my invention,

Figure 1 is an elevation, partly in section, through a pulverizing apparatus embodying my invention;

Figure 2 is a section on the line II—II of Figure 1;

Figure 3 is a perspective view of a portion of the apparatus;

Figure 4 is a view corresponding to Figure 1 but showing a modified form of the invention, and

Figure 5 is a section on the line V—V of Figure 4.

In the embodiment of the invention illustrated in Figures 1 and 2, coal, which has been previously crushed to the usual fineness before being subjected to the action of apparatus of this character, is conveyed by a spiral conveyor 2 to a chute 3 and into a fluid conduit 4. The coal as it drops down the chute 3 meets a deflector 5. This deflector aids the conveying fluid in carrying the coal into the apparatus.

The conveying fluid, which is preferably air, is fed through a header 6 into the conduit 4 and its quantity may be regulated by a suitable damper 7. A suitable heater 6' may be provided in the conduit 6 to preheat the incoming air when pulverizing wet material. The mixture of coal and air enters a primary pulverizing mill 8. A feed ribbon 9, is preferably employed to carry the larger lumps into the apparatus and this ribbon may be extended as far as the chute 3 if necessary.

The interior of the primary mill 8 is corrugated, as best shown in Figure 2, and is preferably of a generally conical form. The mill 8 contains a quantity of balls 10 of varying size. The outlet of the mill 8 comprises an axial passage 11 containing helical ribbons 12 which prevent egress of the balls 10 as the mill is rotated but allow a free passage for the air and coal.

10 As the air and coal leave the passage 11 they strike a deflector 13 which reverses their flow and directs them into a second reducing mill 14 which surrounds the mill 8. This mill is provided with grinding balls 15 and is carried on suitable rollers 16. The mill may be driven in any desired manner as by a ring gear 17 meshing with a driving pinion (not shown). The mill 8 is supported within the mill 14 by spacers 20 8^b, preferably at both ends. These spacers are preferably narrow to minimize obstruction of the passages.

At times it may be desirable to introduce auxiliary air at some point along the fluid path. For this purpose, I provide a conduit 18 leading from the header 6 and provided with a damper 19 for regulating the quantity of auxiliary air or for cutting it off entirely as may be determined by such conditions as the moisture in the coal or the quantity of coal being ground. The auxiliary air passes around the deflector 13 and helps to carry the coal through the neck 20 of the drum 14.

35 The powdered coal leaves the apparatus through a conduit 21 and may be taken directly to a furnace to be consumed or to a storage tank as desired.

40 A fan 22 may be employed to provide a suction and insure proper air flow through the apparatus. In addition to the fan 22 the air in the header 6 may be maintained under moderate pressure. If such is the case, the pressure in the mill is likely to 45 be above atmospheric and this may result in leakage of the finely divided coal from the apparatus. I overcome this by extending the deflector 13 beyond the joint 23 between the neck 20 and the conduit 18.

50 This construction provides an efficient air seal for the rotating joint and effectually eliminates all leakage at this point. A similar air seal may be provided for the joint 24, if necessary, but the fan 22 will generally maintain a sub-atmospheric pressure at this point and obviate any necessity for such construction.

It will be noted that the drums of both the reducing mills are of varying cross-section. This results in a varying velocity of air through the mills and, as explained above, effects a suitable gradation of the coal particles. The balls 10 and 15 are also graded in size, the drum 8 containing 60 larger balls than those in the drum 14.

There is, moreover, a gradation of ball sizes in each drum and the general tendency is for the heavier balls to remain at the larger portions of the drum where the impact is most necessary for reducing large lumps, 70 the size of the balls decreasing as the drum diameter is reduced. This results in an efficient graded pulverizing system starting out with large balls and a large diameter drum and terminating in small balls and a 75 smaller drum size. This same gradation is present in both drums and the size of the balls in the two drums is such that the grinding is progressively finer from one end of the air path to the other. Generally speaking, the effect of the mill 8 is to 80 reduce by impact while the drum 14 effects the final minute reduction by attrition.

There is also provided a free air path above the balls which provides an unobstructed course for such particles as may be reduced to final size at any point in the apparatus. This final size may be determined by properly controlling the air supply. The auxiliary air which enters around the deflector 13 is partially obstructed by a plate 25, as shown in Figure 3. This plate may be rotated to any desired position by a handwheel 26. This is desirable since the auxiliary air will take the path of least resistance and would normally travel through the upper half of the mill 14. The plate 25, however, closes off a portion of the space around the deflector 13 and with the plate positioned as shown in Figure 1 100 most of the auxiliary air will travel through the lower half of the drum. Since the coal particles tend to fall, it will be seen that the auxiliary air will pick up the larger particles and materially assist in carrying them into the mill 14. If desired, the plate 25 may be made smaller than the interior diameter of the air conduit at that point to provide a passage for a certain amount of air all around the opening 20 in 105 order to better insure a complete air seal of the joint 23. The plate 25 may be rotated to shift the inlet of the auxiliary air as desired.

In the embodiment of my invention shown 115 in Figure 4, the material is first ground in the outer drum 27 and then passes through the inner drum 28 for final reduction. In this view, parts corresponding to similar parts in Figure 1 have been given the same 120 reference characters with the suffix *a* thereto. A blower 27 may be provided if desired, and either forced or induced draft alone, or both together, may be used, as desired, to supply the conveying fluid.

Figure 5 shows another form of drum corrugation which may be employed if desired.

It will be noted that a relatively high velocity is imparted to the air in all of the conduits. This serves to keep the passages 125

clear and prevents any clogging therein. As soon, however, as the air reaches a grinding drum its velocity is immediately reduced to a great extent by the increase in 5 cross-sectional area. The reduction in velocity immediately results in a deposition of the entrained particles which are graded according to their mass. Both the inner and outer surfaces of the inside drum are 10 utilized, particularly the larger portion thereof.

This invention provides a pulverizer of high efficiency since the particles to be reduced are graded in accordance with the 15 gradations of the pulverizing system enabling every portion thereof to work at maximum efficiency and resulting in a uniform product.

While I have illustrated the preferred embodiment of my invention, it will be understood that it is not limited thereto but may be embodied in other constructions within the scope of the following claims.

I claim:

25 1. The method of pulverizing coal, which includes carrying coal through a pulverizing chamber by a fluid stream, substantially continuously varying the velocity of the fluid stream as it travels through the pulverizing 30 chamber, utilizing the stream to carry the coal from the pulverizing chamber to a second pulverizing chamber, and materially decreasing the velocity of the fluid as it passes into the second pulverizing chamber.

35 2. The method of pulverizing coal, which includes carrying coal through a pulverizing chamber by a fluid stream, utilizing the fluid stream to carry the coal from the pulverizing chamber to a second pulverizing chamber, materially decreasing the velocity 40 of the fluid as it passes into the second pulverizing chamber, and substantially continuously varying the velocity of the fluid stream in at least one of the pulverizing chambers as it passes therethrough.

45 3. The method of pulverizing coal, which includes carrying coal through a pulverizing chamber by a fluid stream, utilizing the fluid stream to carry the coal from the pulverizing chamber to a second pulverizing chamber, introducing supplemental air between the pulverizing chambers, and materially decreasing the velocity of the fluid as it passes into the second pulverizing chamber.

50 4. The method of pulverizing coal, which includes delivering the coal to a pulverizing chamber by a fluid stream, materially decreasing the velocity of the stream at a point in the pulverizer to deposit particles 55 at a desired point, and substantially continuously varying the velocity of the stream as it passes through the pulverizer.

5. Pulverizing apparatus including a pulverizer, means for passing a conveying 60 fluid therethrough, means for feeding ma-

terial to the pulverizer, and auxiliary means for supplying conveying fluid at a point beyond that where the original fluid is supplied and adapted to convey material to another portion of the pulverizer substantially as described. 70

6. Pulverizing apparatus including a pulverizer, means for passing a conveying fluid therethrough, means for feeding material to the pulverizer, auxiliary means for supplying conveying fluid at a point beyond 75 where the original fluid is supplied and adapted to convey material to another portion of the pulverizer, and means for adjusting the point of introduction of auxiliary fluid, substantially as described. 80

7. Pulverizing apparatus including a plurality of pulverizing mills, means for passing a conveying fluid through said mills, whereby the material travels through the 85 mills in succession, means for introducing auxiliary conveying fluid between mills, means for separately controlling said means, substantially as described.

8. Pulverizing apparatus including a plurality of pulverizing mills, means for passing a conveying fluid through the mills and means for varying the velocity of the conveying fluid as it passes through each of the mills, substantially as described. 90

9. Pulverizing apparatus, including a plurality of graded pulverizing mills, and means for passing a conveying fluid successively therethrough, each of the mills being so shaped as to vary the velocity of 100 the conveying fluid as it passes therethrough and thus effect a corresponding gradation in the size of the particles deposited at different points through said graded pulverizing mills, substantially as described. 105

10. Pulverizing apparatus including a plurality of pulverizing mills, means for passing a conveying fluid through the mills, means for introducing auxiliary fluid between the mills, means for maintaining a 110 free fluid path through the mills, and means for shifting the inlet of the auxiliary fluid with respect to the free fluid path, substantially as described.

11. Pulverizing apparatus including a 115 mill having a plurality of rotary pulverizing chambers contained within one another, means for passing a conveying fluid through the chambers in succession and means for introducing auxiliary fluid between the 120 chambers, substantially as described.

12. Pulverizing apparatus including a pulverizer, means for passing a conveying fluid therethrough, means for feeding material to the pulverizer, auxiliary means for supplying conveying fluid at a point beyond 125 that where the original fluid is supplied, and means for heating the medium, substantially as described.

13. Pulverizing apparatus including a 130

mill having a plurality of pulverizing chambers, means for passing a conveying fluid through said chambers, whereby the material travels through the chambers in succession, means for introducing auxiliary conveying fluid between the chambers, and means for heating the medium, substantially as described.

14. Pulverizing apparatus including a plurality of pulverizing mills, means for passing a conveying fluid through the mills, means for varying the velocity of the conveying fluid as it passes through each of the mills, and means for heating the medium, substantially as described.

15. Pulverizing apparatus including a plurality of pulverizing mills, and means for passing a conveying fluid through the mills, at least one of the mills having means for varying the velocity of the conveying fluid as it passes therethrough.

16. Pulverizing apparatus including a mill having a plurality of rotary pulverizing chambers contained within one another, and means for passing a conveying fluid through said chambers in succession.

17. Pulverizing apparatus including a ball mill having a plurality of rotary pulverizing chambers contained within one another, and means for passing a conveying fluid through said chambers in succession, at least one of said chambers having a portion which is of diminishing cross sectional area and being provided with balls of different sizes.

18. Pulverizing apparatus including a ball mill having two rotary pulverizing chambers contained within one another, and means for passing a conveying fluid through said chambers in succession, the chambers each having a portion which is of diminishing cross sectional area and each being provided with balls of different sizes.

19. In pulverizing apparatus, a rotary ball mill having a portion which is of diminishing cross sectional area, balls of different sizes within the mill, and means for passing a conveying fluid through the mill.

20. Pulverizing apparatus including two pulverizing chambers contained within one another, and means for passing a conveying fluid through said chambers in succession, each of said chambers constituting a fluid path of diminishing cross-sectional area.

21. Pulverizing apparatus including a mill having a plurality of rotary pulverizing chambers contained within one another, and means for passing a conveying fluid through said chambers in succession, each of said chambers having a conical portion the apexes of said portions being at opposite ends of the mill, the chambers providing a fluid path having a plurality of portions of diminishing cross-sectional area, substantially as described.

22. Pulverizing apparatus including a mill having a plurality of rotary pulverizing chambers contained within one another, and means for passing a conveying fluid through said chambers in succession, each of said chambers being of diminishing cross sectional area, the diminution being in the direction of the fluid flow through such chamber, substantially as described.

23. Pulverizing apparatus including a mill having a plurality of rotary pulverizing chambers contained within one another, each of said chambers being of diminishing cross-sectional area, the smaller ends of the chambers being at opposite ends of the mill, and means for passing a conveying fluid from the larger to the smaller end of the chambers in succession.

24. Pulverizing apparatus including a mill having a plurality of substantially conical pulverizing chambers contained within one another, the chambers being substantially coaxial and having their apex portions lying alternately at one end of the mill and the other, and means for passing a conveying fluid through said chambers in succession.

25. Pulverizing apparatus including a mill having a plurality of substantially conical pulverizing chambers contained within one another, the chambers being substantially coaxial and having their apex portions lying alternately at one end of the mill and the other, and means for passing a conveying fluid from the innermost to the outermost chamber in succession.

26. Pulverizing apparatus including a mill having a plurality of substantially conical pulverizing chambers contained within one another, the chambers being substantially coaxial and having their apex portions lying alternately at one end of the mill and the other, and means for introducing conveying fluid at the base portion of one of the chambers and passing it to the apex portion of said chamber thence to the base portion of a succeeding chamber and through said chamber.

27. The method of pulverizing coal which includes passing a conveying fluid through a pulverizing system, and alternately increasing and decreasing the velocity of the conveying fluid as it passes therethrough, at least one of the changes in velocity being relatively gradual, substantially as described.

28. The method of pulverizing coal which includes passing a conveying fluid through a pulverizing system, and alternately increasing and decreasing the velocity of the conveying fluid as it passes therethrough, the increases in velocity being gradual and the decreases in velocity being relatively sudden, substantially as described.

29. Pulverizing apparatus including a mill having a plurality of successive grind-

ing means adapted to reduce the material to successively smaller sizes, the mill having an inlet for conveying fluid, and means for passing a conveying fluid through the mill and successively past the pulverizing means, the mill being adapted to provide a velocity of the fluid stream which increases to correspond to the increased fineness of the particles produced by the grinding means, the mill having an outlet for the fluid and the pulverized material carried thereby and being fluid-tight between the inlet and the outlet, substantially as described. 10

In testimony whereof I have hereunto set my hand.

LOUIS DE MARKUS.
